UNITED STATES PATENT OFFICE.

WILLIAM E. BAHR, OF WASHINGTON, DISTRICT OF COLUMBIA.

ADJUSTABLE FLUE CLEANER FOR HEAT RADIATORS.

Application filed February 20, 1919, Serial No. 278,145. Renewed August 22, 1922. Serial No. 583,632.

To all whom it may concern:

Be it known that I, WILLIAM E. BAHR, a citizen of the United States of America, residing at Washington, in the District of Columbia, have invented certain new and useful Improvements in Adjustable Cleaners for Heat Radiators, of which the following is a specification.

The primary object of the invention is 10 the provision of an auxiliary flue heater whereby the waste products of combustion from any burner may be utilized for heating purposes thereby utilizing heat units without additional expense and which would 15 otherwise be lost, advantageous cleaning means being incorporated in the structure normally maintaining the same at a high degree of efficiency.

A further object of the invention is to 20 provide an auxiliary flue heater with a simple and efficient means for successively cleaning the plurality of flues thereof without the necessity of employing an outside cleaner, the device being readily adjustable 25 during the cleaning operation which is accomplished in a cleanly and sanitary manner by preventing the escape of any gases or dirt from the device while cleaning the same.

With these and other objects in view, 30 it will be readily apparent as the nature of the invention is better understood, the same consists of the novel combination and arrangement of parts hereinafter fully described, illustrated in the accompanying drawing and then claimed.

In the drawing forming a part of this application and in which like characters 40 designate corresponding parts throughout the several views,

Figure 1 is an elevational view of my invention in its entirety.

Figure 2 is a longitudinal sectional view taken therethrough axially of one of the flues 45 thereof and illustrating the cleaner in its normal enclosed position.

Figure 3 is a fragmentary detail sectional view taken radially of one of the drums or heads of the device showing the pivotal connecting means.

Figure 4 is an end elevational view of the invention and

Figure 5 is a view similar to Fig. 4 with the revoluble end cap with the cleaner and accompanying parts removed.

My improved radiator and cleaner con-

sists of oppositely positioned tubular heads or drums 10 and 11, either of which may constitute the inlet or outlet drum for products of combustion derived from any manner 60 of burner or heater such as a coal, wood, gas or oil burner, a plurality of tubes or flues 12 connecting the said drums together for the passing of products of combustion therethrough, while similar thimbles 13 65 and 14 communicate with the interior of the drums 10 and 11 respectively being relatively mounted thereon at any point and in any manner desired. My invention is designed for positioning in a room or compartment at any suitable distance from the main burner or heater with one of said thimbles 13 and 14 adapted to receive the products of combustion therefrom while the other thimble serves as an outlet communicating with the discharge flue or chimney. The waste products of combustion which are passed in this manner through my device effect a heating of the surrounding atmosphere by the free radiation of heat 70 units without adding to the expense of operating the main heater. It will be understood that my invention may be positioned vertically, horizontally or otherwise as found desirable, is ornamental in appearance and 75 consumes but little room while performing its function of heat radiation.

One of the drums such as 11 has a closure cap 15 in the form of a disk revolvably mounted thereon with an annular flange 90 16 fitting within the end of the drum while the peripheral portion 17 of the disk 15 projects outwardly of the flange 16 beyond the upper edge or rim 18 of the drum 11. A bolt 19 is centrally journaled through the drum 11 and through the disk 15 having a head 20 beneath the drum between the flues 16 while a washer 21 and a removable nut 22 are provided upon the opposite end of the bolt 19 outwardly of the cap 15 95 whereby the latter is rotarily mounted upon the drum 11. A suitable form of cup-shaped plug or closure 23 is normally maintained by friction in its closing position in a circular opening 24 through the cap 15, 100 the said opening being eccentrically positioned adapted for axial alignment with all of the flues 12 during each revolution of the cap 15. A cleaner for the flues 12 consists of a rod 25 slidably mounted through the plug 23 and extending through the drum 11 for normal positioning axially of any one 105 110

of the flues 12 as best illustrated in Figure 2 of the drawing, a cleaning head or enlargement 26 upon the end of the rod 25 being normally positioned in the opposite drum 5 10 when the cleaner is not in use.

A cylindrical handle 27 upon the opposite end of the rod 25 outwardly of the plug 23 is adapted to impart longitudinal sliding movement to the rod 25 for forcing the head 10 15 through the adjacent flue 12 for cleaning the same of soot and dirt accumulations therein, the handle 27 having a suitable packing 28 preventing the escape of any products of combustion from the drum 11 15 around the rod 25 when the cleaner is not in use.

A spring 29 is riveted or otherwise secured as at 30 exteriorly of the drum 11 having a free end portion 31 triangular in 20 cross section adapted for engaging within spaced notches 32 in the peripheral portion of the cap 15 when the opening 25 is positioned in axial alignment with the separate flues 12 for accurately positioning the rod 25 25 for the cleaning thereof.

The complete operation of the invention will be fully understood from this detailed description thereof, the device being installed as noted and preferably positioned vertically as herein illustrated, the rod 25 may be withdrawn by means of its handle 27 positioning the cleaning head 26 within the drum 11 and permitting the free rotation of the cap 15 for engaging the spring portion 31 successively in the notches 32 whereby the reciprocations of the rod 25 successively cleans the flues 12 as heretofore noted.

A compact form of auxiliary radiator is provided that is readily kept free and clean 40 from soot and dirt in the manner described for rendering the same fully efficient at all times, for the passing of waste products of combustion therethrough and utilizing such products for suitable heating purposes.

The spring end 31 has its apex 33 preferably rounded permitting the ratcheting rotation of the cap 15 for removing and reseating the spring successively in the notches 32 it being understood that the said notches 50 55 are radially arranged relatively of the pivot bolt 19 for passing through the axial planes of the flues 12, the opening 24 being in the radial line of one of said notches 32 in a radial distance corresponding to the axes 55 of the flues 12 relatively of said bolt 19.

While the form of the invention herein

shown and described is what is believed to be the preferred embodiment thereof, it is nevertheless to be understood that various forms, modifications and arrangements of the parts may be made without departing from the spirit and scope of the invention as claimed.

What I claim as new is:—

1. A device of the class described including inlet and outlet drums for products of combustion connected by a plurality of radiating flues, a closure cap journaled upon the end of one of said drums having a projecting peripheral portion provided with notches outwardly of the rim of the drum spaced apart upon radial lines passing through the planes of the axes of said flues, a spring retainer exteriorly carried by said drum having a triangular end adapted for seating successively within said notches and a removable cleaner slidably positioned through the cap and adapted for operative registering with said flues during the seating of the spring within the notches. 65 70 75 80

2. A heat radiator comprising a drum, flues concentrically projecting from one end thereof, a disk upon the opposite end of the drum, centrally journaled for rotation thereon, and having an opening adapted for successive registry with said flues, during the turning of the disk, the said disk having a peripheral portion outwardly of the drum, provided with notches equally spaced apart, upon radial lines, passing through the axial planes of the flues, one of said notches being in the same radial plane of the disk as said opening, and a spring secured exteriorly to the drum with a triangular portion adapted for seating in said notches during the registry of the opening with said flues. 90 95

3. The elements of claim 2 with the following addition: A plug frictionally secured in said opening, a rod slidably mounted through the plug axially of the opening, 100 adapted for reciprocation through said flues, successively, a head upon the inner end of said rod, a handle upon the opposite end of the rod outwardly of the plug, and a packing upon the rod at the inner end of the handle adapted for seating upon the plug to prevent the escape of gases and particles from the drum when the drum is in use as a heater.

In testimony whereof I affix my signature.

WILLIAM E. BAHR.
